UNITED STATES PATENT OFFICE.

ALBERT MATHA AND JAMES F. LESKO, OF CHICAGO, ILLINOIS.

BURGLAR-ALARM AND LOCK.

1,314,086.

Specification of Letters Patent. Patented Aug. 26, 1919.

Application filed November 1, 1917. Serial No. 199,640.

To all whom it may concern:

Be it known that we, ALBERT MATHA and JAMES F. LESKO, citizens of the United States, and residents of Chicago, in the county of Cook and State of Illinois, have invented a certain new and useful Improvement in Burglar-Alarms and Locks, of which the following is a description, reference being had to the accompanying drawings, which form a part of our specification.

Our invention relates more particularly to a device which may be readily applied to any door-casing or jamb and preferably in proximity to the usual lock of the door to operate in conjunction therewith.

The invention contemplates an alarm which will be set in operation or sounded either through the manipulation or turning of the door-knob and therefore in the withdrawal of the latch-member or bolt operated by the knob; or it may be set in operation through the movement or throwing of the lock-bolt or member induced by manipulation of the lock-key; or where the ordinary style of lock is used, the alarm may be set in operation by the movement of both the knob-actuated latch-member and the key-operated bolt.

The invention also contemplates a construction which will provide an auxiliary or safety bolt adapted to be thrown into locking or bolting position when the usual or regular locking bolt of the door has been thrown by a suitable key; the actuation of the mechanism, through movement of the regular door-lock or bolt causing the alarm to be sounded and the safety or supplemental bolt to be "shot" so that opening of the door will be prevented.

The operation and advantages of our invention will be readily comprehended from the following detailed description of the exemplification illustrated in the accompanying drawings wherein:

Figure 1 illustrates an embodiment of our invention in perspective, applied to a door-casing or jamb, with portions of the case or housing broken away to disclose certain of the internal mechanisms or elements.

Fig. 2 is a cross sectional plan view taken just above the bell of the alarm.

Fig. 3 is a sectional view taken on the line 3-3 of Fig. 2 looking in the direction of the arrows.

Fig. 4 illustrates the mechanism in eleva-

tion with the front plate of the housing and alarm mechanism removed.

Fig. 5 is a perspective view of the mechanism seen looking to the left from line 5-5 in Fig. 4.

Fig. 6 is a perspective view of the mechanism looking to the right from line 5-5 in Fig. 4.

Fig. 7 is a detail sectional view taken on the line 7-7 of Fig. 4 looking downwardly.

The exemplification chosen to illustrate our invention is shown in connection with an ordinary well-known type of lock, with which the door-casing or jamb is provided with an escutcheon plate provided with the usual slots for the reception of the latch-member operated by the knob and the lock-bolt controlled by the key. In the specific exemplification, the operating mechanism is inclosed in a suitable housing or casing 10, preferably of sheet metal, adapted to be secured to the door jamb, as for example by the screws 11 which pass through the flanges 12, 12 of the housing; the flanges 12 being adapted to overlap the sides of the door-jamb A. The device is preferably secured on the door-jamb in proximity to the escutcheon plate B which covers one or more slots in the door-jamb; the escutcheon plate being provided with the slot or opening 13 adapted to receive the ordinary lock-latch, while the other opening or slot 14 is adapted to receive the usual lock-bolt.

In its specific form, the device comprises an ordinary spring-controlled alarm bell, shown at 15 in Figs. 1 and 2; the alarm or bell shown being of the well known type usually known as a bicycle-bell, wherein the spring is wound and placed under tension by turning the bell proper. The spring is incased in the barrel or shell 16, and the tapper or knocker 17 is given vibratory movement against the rim of the bell proper through the action of the star wheel 18 actuated through suitable pinions controlled by the spring; the star-wheel 18 being adapted to have slight frictional contact with the double dog or pallet 19 to which the tapper or knocker 17 is secured. The tapper or knocker 17, and its escapement member or pallet 19, are held in frictional holding contact with the star-wheel 18 by means of a flat spring 20, secured in any convenient way to one of the walls of the alarm mechanism, which passes beneath the

arm of the tapper 17, as clearly shown in Fig. 1.

As the alarm mechanism shown is of a well known construction, and *per se* forms no part of our invention, a more specific or detailed description of this part of the mechanism need not be entered into, except to say that instead of employing a spring-actuated bell, an electrically operated alarm 10 may be employed and as readily applied as the construction illustrated.

The spring member or knocker-holder element 20 has its free end bent forwardly, as shown at 21, so as to be engaged by the fingers or prongs 22 and 23, preferably formed integral with the link-members 24 and 25, respectively.

The links 24 and 25 are slidably mounted in the casing or housing 10, having their forward ends pivotally connected at 26 and 27 to the rock-levers 28 and 29, respectively. The rock-levers 28 and 29 have their ends bent in the angular manner shown in Fig. 1 with the free ends thereof given a crank formation which are adapted to extend into the paths of the lock-latch and lock-bolt, respectively; the levers or members 28 and 29 extend through the rear wall of the casing 10 and through suitable grooves in the door-jamb which connect with the socket in the door-jamb; the grooves being such that members 28 and 29 may oscillate or rotate about their axes.

The opposite ends of links or members 24 and 25 are preferably shown slightly reduced, see Figs. 4 and 6, and these ends are each provided with a coil-spring 30 and 31, respectively. One end of spring 30 is secured to member 24, while the other end is secured to a bell-crank lever 32 which is pivoted at 33 on the rear wall of the shell or casing, with the free end of the bell-crank lever 32 extending through a suitable slot or opening 34 in the end wall of the housing or casing. The spring 31 has one end secured to member 25 and the other end secured to bell-crank lever 35 which is pivoted at 36 to the casing, with the free end of the lever 35 disposed through a suitable slot 37 in the end wall of the casing.

At suitable points, intermediate of their ends, both links or members 24 and 25 are provided with small angularly disposed lugs 38 and 39, respectively, see Figs. 4 and 5, which are adapted to engage with an arm or member 40. The member 40 is preferably made separate from and adjustably secured to the tumbler or member 41 pivoted at 42 to the wall of the casing. The member 41 is shown provided with the upwardly disposed angular portion, see Figs. 4 and 5, having lugs 43 between which member 40 is held; the member 40 being provided with an elongated slot at its lower end for the passage of a suitable set-screw 44 whereby

member 40 is maintained in its adjusted position, so that arm 40 may be raised or lowered so as to come into the path of the lug 38 and lug 39 or simply the latter. With the member 40 in the position shown in Figs. 4 and 5, it will merely be engaged by the lug 39 of link member 25, while lug 38 of link member 24 is free to pass thereover. The member 41 is controlled by the action of a suitable spring 45 which, in the drawings, is shown wound about a post 46 on the rear wall of the casing, with one end bearing against the boss or lug 47 formed on the wall of the casing, while the other end may be secured to member 41 so as to insure positive relation with member 41; the spring exerting downward pressure on the forward end of member 41, thereby maintaining it in holding engagement with an auxiliary bolt-member 48.

Bolt-member 48 is slidably mounted in the casing 10, and held in place by a suitable guide-way 49; the forward end of the bolt member being adapted to pass through a suitable opening, as at 50, in the front end of the casing, see Figs. 1 and 4. The rear end of bolt-member 48 is shown preferably terminating in a reduced or pin portion, see Fig. 4, to receive and guide an expansible coil spring 51, the other end whereof is shown encircling a boss 52 formed integral with the rear end of the casing. It is evident from the construction shown that bolt member 48 will compress the spring 51 when the bolt-member is in its normal or retracted position, as shown in Fig. 4, so that the bolt-member will at all times be under spring pressure and made to slide forwardly through the slot 50 in the forward end of the shell, as soon as it has been released through proper movement of tumbler member 41. Member 41 has its forward end bent, as shown at 53, to engage with a lug 54 on the upper side of bolt member 48, thereby holding bolt member 48 against the outward pressure of spring 51.

The bolt member 48 is shown provided with a recess at 55 preferably adjacent the forward end thereof adapted to receive a portion of a pawl 56 which is pivoted at 57 to the front end of the casing so as to swing transversely of the casing. The lower end of pawl 56 extends through a slot 58 in the bottom of the casing, see Figs. 4 and 5, to enable it to be manipulated from the casing exterior and to be moved out of holding engagement with bolt 48 when it is desired to set the device so that the door will be locked by bolt 48 in the event that the bolt of the door-lock has been withdrawn or manipulated by a suitable key from the door-exterior.

With the levers 32 and 35 in the positions shown in Figs. 4 and 6, namely in a position whereby springs 30 and 31 will be com-

pressed which forces link-members 24 and 25 forwardly, no tripping or releasing action will result by any movement of either the door-latch or lock-bolt, or both. In order to set the mechanism, levers 32 and 35, either one or both as desired, must be shifted about their respective pivotal points so as to distend their respective springs 30 and 31 and thus apply pulling action on the link members 24 and 25, respectively. A pulling action on links 24 and 25, in the direction of springs 30 and 31, will cause the rock-levers or trip members 28 and 29 to be rotated on their axes in a direction which will force the free crank portions toward the front of the slot-ways or openings 13 and 14 in the escutcheon plate member B; in other words will force the crank end portions of the members or rock-levers 28 and 29 into firm engagement with the latch member and the lock-bolt, respectively, and thus cause the crank portions of the levers to move into the path of the knob operated latch-member of the door-lock and the locking bolt when the latter are withdrawn from their respective openings or slots. As is apparent, the crank ends of the rock-levers will be yieldingly held in the paths of the latch member and bolt so that the rock-levers will be forced back to normal positions when the door is closed and the latch replaced or the locking bolt returned to its socket. In other words, the device having once been "set," this condition will automatically maintain or be restored when the latch-member and locking bolt are returned to their slots.

When the device is installed, the escutcheon plate B is first removed and the door-jamb provided with grooves at proper points so as to be covered by the plate B when it is replaced, so that rock-levers 28 and 29 will not be accessible from the door-exterior. With the device in position and the rock-levers in the condition just described, the moment the knob of the door is turned so as to withdraw the latch-member from its slot 13, rock-lever 28, being under the influence of spring 30, will rock on its axis, with the crank end portion following the direction of movement of the latch-member, thereby permitting link 24 to be drawn rearwardly by its spring 30, causing lug 22 on link 24 to come into operative engagement with the knocker-holding element or spring 20, so as to depress the same out of holding engagement with the knocker 17 and thereby allow it to be operated through the action of the star wheel 18 and pallet 19, causing an alarm to be sounded the moment the knob of the door has been turned to release the latch.

On the other hand, if the door has been locked, and it is desired to set the alarm in the event of any movement of the locking

bolt, then lever 35 is oscillated downwardly in Fig. 4 so as to place spring 31 under tension and exert a pull on link 25, which imparts rocking movement to member 29 and holds the crank end portion of the latter in firm yielding engagement with the end of the bolt. The moment the bolt has been withdrawn from its socket in the escutcheon plate B, member 29 will rock on its axis, causing the free end or crank portion to follow the direction of movement of the bolt, while link-member 25 will move to the rear of the shell or casing 10 in the direction of the pull exerted by spring 31; such movement of link 25 will cause its lug 23 to be brought into striking engagement with the knocker-holding element 20 and depress the latter out of holding engagement with the knocker, allowing the operation thereof through the action of the escapement as previously described and the alarm sounded; the bell continuing to ring as long as the mechanisms remain in the positions just described; in other words until the bolt has been "shot" into place so as to again return lever 29 and link 25 to normal or "set" position.

Should it be desired to have the auxiliary locking mechanism operate—either when the latch has been withdrawn through a proper turning of the knob, or when the bolt of the lock has been withdrawn,—pawl 56 is moved out of holding engagement with bolt 48, so that reciprocation of either link 24 or link 25, or both, through the pulling action of their respective springs, will cause the lug 38 on link 24 or lug 39 on link 25, or both (provided member 40 has been adjusted or raised so as to come into the path of both lugs) to come into striking engagement with member 40 and thereby tilt the spring-controlled member 41 so as to raise it out of the path of lug 54 on bolt 48 and thereby allow the compressed spring 51 to immediately force bolt 48 outward and into the path of the door and prevent the same being opened. It will be understood, of course, that the auxiliary or safety lock 48 is "set" or placed in inoperative position by proper movement of pawl 56 when the occupants intend to leave the premises, during which period levers 32 and 35, either one or both, are set so that an alarm will be sounded without causing bolt 48 being released to prevent the occupant entering.

In order to adapt the device to different styles of locks, as for example a Yale lock where a single latching element is employed, the crank-ends of either rock member or shaft 28 or shaft 29, or both, are shown removably secured at 59 to the remainder of the shaft, as two crank-arms will not be needed with locks of that character. The entire rock shaft if desired may be made removable and thus obviate the necessity of

4
providing more than one groove or channel in the door-jamb.

It is evident also that an electrically controlled alarm may be employed instead of a spring-controlled alarm, in which event the holding member 20 may constitute the circuit-controlling or contact-forming member; the invention being readily adapted to either form of automatic alarm mechanism.

10 We have shown and described a simple form of the invention and its adaptation to a door provided with a usual type of lock, employing a latching member and a locking bolt, although it is evident that where the lock is merely provided with a single latching or locking element but one set of alarm actuating elements need be employed; the invention being readily adaptable to different situations and therefore capable of having expression in somewhat different mechanical form without, however, departing from the spirit of the invention.

What we claim is:—

1. A device of the class described, comprising a spring-actuated element adapted to extend into the path of the latching member of a lock and in yielding relation therewith so as to follow the direction of travel of said latching member, means whereby said spring-actuated element is controlled, an automatic alarm mechanism, means intermediate of the alarm mechanism and said spring-actuated element whereby operation of the alarm mechanism is controlled, and an auxiliary locking member adapted to be actuated when said spring-actuated element is permitted to move by the withdrawal of the latching member of the lock from latching position.

2. A device of the class described, comprising a pair of oscillatingly mounted members adapted to respectively extend into the paths of the latching member and bolt member of a lock, separate spring-controlled means for each of said oscillatingly mounted members whereby the oscillatingly mounted members may be independently controlled so as to be controlled by movement of the latching member and the bolt member, an automatic alarm mechanism, and means intermediate of the first mentioned means and said alarm mechanism whereby the alarm mechanism is permitted to operate when either one or both of said oscillatingly mounted members are permitted to move by the withdrawal of the latching member or the locking bolt.

3. A device of the class described, comprising means adapted to yieldingly extend into the path of the latching element of a lock and arranged to move therewith, means whereby the first mentioned means is controlled, automatic alarm mechanism arranged in operative relation with the second mentioned means and adapted to oper-

ate when the first mentioned means functionates through the withdrawal of the latching element of the lock, an auxiliary bolt adapted to be released when the first mentioned means functionates through the withdrawal of the latching element, and means whereby said auxiliary bolt may be controlled.

4. A device of the class described, comprising spring-controlled means arranged to extend into the path of the latching element of a lock and be controlled thereby, automatic alarm mechanism adapted to be controlled by said means when the latter functionates through the withdrawal of the latching element of the lock, a spring-controlled auxiliary-bolt, and means intermediate of the first mentioned means and said bolt whereby the latter is released when the first mentioned means functionates through the withdrawal of the latching element of the lock.

5. A device of the class described, comprising a rock-shaft, one end whereof is adapted to extend into the path of the latching element of the lock, means whereby the rock-shaft is controlled and made to functionate when the latching element is withdrawn from latching position, an auxiliary bolt, and means intermediate of the bolt and the first mentioned means whereby the bolt is released and caused to move into bolting position.

6. A device of the class described, comprising a rock-shaft, one end whereof is arranged in the path of the latching element of a lock, a spring-controlled member operatively connected with said rock-shaft whereby the latter is caused to rock in the direction of movement of the latching element, a spring-controlled bolt, and means intermediate of said bolt and the spring-controlled member whereby the bolt is released when the rock-shaft rocks in the direction of movement of the latching element to unlatching position.

7. A device of the class described, comprising a member adapted to extend into the path of the latching element of a lock, means whereby said member is yieldingly held in contact with said latching element and caused to move therewith, automatic alarm mechanism, a holding member whereby the alarm is held against operation, means intermediate of the first mentioned member and said holding member whereby the latter is moved out of holding position and the alarm permitted to operate when the first mentioned member is permitted to move through the withdrawal of the latching element, and an auxiliary spring-actuated bolt adapted to be released by the movement of said first mentioned member.

8. A device of the class described, comprising an oscillatingly mounted member

- adapted to extend into the path of the latching element of a lock, a spring-actuated member operatively connected with the oscillatingly mounted member so as to cause the latter to oscillate when the latch element is withdrawn from latching position, automatic alarm mechanism, a holding member whereby the alarm is held against operation, means intermediate of the spring-actuated member and said holding member whereby the latter is moved out of holding position and the alarm permitted to operate when the oscillatingly mounted member actuates through the withdrawal of the latching element, means whereby the spring-actuated member may be controlled, a spring-controlled auxiliary bolt, and means intermediate of said bolt and spring-actuated member whereby said bolt is released when the oscillatingly mounted member moves with the latching element to unlatching position.
9. A device of the class described, comprising a rocking-member adapted to extend across the path of the latching element of a lock, a reciprocating member operatively connected with said rocking-member, means whereby the reciprocating member is placed under spring pressure and the rocking-member yieldingly maintained in contact with the latch member, automatic alarm mechanism, means whereby the alarm is held against operation, and means intermediate
- 5 of the reciprocating member and said second mentioned means whereby the latter is actuated and the alarm mechanism released 35 when the reciprocating member with the rocking-member is permitted to move through the withdrawal of the latching element.
10. A device of the class described, comprising oscillatingly mounted means adapted to extend across the path of the latching element of a lock, reciprocatingly mounted means operatively connected with said first means so as to control the same, means 40 whereby said second means is placed under pressure and the first means thereby yieldingly forced into contact with the latching element and made to move therewith and the alarm mechanism thereby "set", automatic alarm mechanism, and a member normally holding the alarm-sounding element of said alarm mechanism against operation, said member being disposed in the path of a portion of said reciprocatingly mounted 55 means and adapted to be moved out of holding relation thereby when the oscillatingly mounted means follows the outward or unlatching movement of the latching element.
